UNITED STATES PATENT OFFICE.

RALPH COLLING, OF BENTON COUNTY, OREGON.

MUSICAL INSTRUMENT.

1,246,055.

Specification of Letters Patent. Patented Nov. 13, 1917.

Application filed December 27, 1916. Serial No. 139,069.

To all whom it may concern:

Be it known that I, RALPH COLLING, a citizen of the United States, residing in Benton county, State of Oregon, have invented 5 a new and useful Improvement in Musical Instruments, of which the following is a specification, reference being had to the accompanying drawings.

My invention relates to that class of devices wherein tones are mechanically produced from or in connection with tone records and a vibrating diaphragm.

The object of my invention is to provide a device by means of which melodies may be 10 produced from the record of a single standard tone of the human voice, or of an instrument, and which melodies shall be of artistic tone quality and greater precision as a whole than when produced in the ordinary 15 way as a melody; also to produce a pure legato or glide between different pitches of tones recorded from instruments whose nature does not permit such glide to be produced from them. I attain these objects, as 20 well as other advantages, by the construction, combination and arrangement of parts illustrated in the accompanying drawings which form a part hereof.

Figure 1 is a plan view of the device.

Fig. 2 is a side elevation of an upper part 30 thereof.

Fig. 3 is a side elevation of the disk and record.

Fig. 4 is a sectional view of same on the 35 line 4—4 of Fig. 3.

Fig. 5 is a sectional view of part of the tone arm and diaphragm and side view of the slotted needle bar below.

Fig. 6 is an end view of the device with 40 cabinet appertaining to it.

Fig. 7 is a side view of lower part of cabinet illustrating operation of shutter pedal lever.

Like letters and numerals refer to like 45 parts in all views.

A is a cabinet provided with legs.

B is a circular turn table which is rigidly secured at its center upon the upper end of a rotatable shaft 8.

50 C is a vertical tube or horn standard which extends from within the cabinet A to a suitable height above the cabinet. The horn C is provided with a rigid horizontal cross-tube 9 and said horn opens into the center of the tube 9. At the ends of the tube 9 are horizontal tone arms 10. The lat-

ter arms are pivotally mounted at their ends within the ends of the tube 9. The tone arms 10 are also provided with hand grips 11.

60 The arms 10 extend over the turn table B, and the end portions thereof extend vertically downward. About the lower ends of the outer ends of the tone arms 10 are casings 11' rigidly secured. Within the casings 65 are coil springs 12, Fig. 5. The lower ends of the springs engage lower interior shoulders 13 of the casings 11' and the upper ends of the springs 12 engage the upper ends 14 of the telescoping stem 15 of the diaphragm 70 holder 16. The holder 16 has a vertical stem 15 extending into the casings 11'. The holder has a circular horizontal frame at the lower end of its stem which frame has a lower shoulder 17. The holder is also provided at its lower end with a circular screw cap 18 which engages the shoulders 17. A diaphragm 19 is secured horizontally between the shoulders 17 and cap 18. The holder 16 has two finger buttons 20 on its 80 upper surface. A horizontal record needle bar 21 is secured to the center of the diaphragm by the nut 22. The needle bar has a longitudinal slot 23 and a vertical jeweled needle point 24 in its free end. Vertical 85 guide pins 25 are provided in the lower surface of the holder 16 to guide the movement of the bar 21 vertically and prevent its lateral movement.

90 The upper ends of disk arms 26 are rigidly secured on the ends of the tone arms 10. The arms 26 have forks 27 in their lower ends. Horizontal shafts 28 are placed in the lower ends of the forks and have means to secure them rigidly. Rotatable disks 29 are mounted on the shafts 28. Circular tone records 30 are mounted concentrically upon the faces of the disks by means of holding springs 31. The records 30 are of smaller diameter than the disks 29. The springs 100 are so arranged that the records may be quickly removed and others substituted.

At each side of the turn table B, rigidly secured on the case A, is a vertical standard 32 provided with a set screw 33. Extending 105 from one standard to the other and above the turn table B is a fulcrum rod 34. It is rigidly secured at its respective ends by the screws 33. It also passes through each of the slots 23 of the needle bars 21. The rod 34 is constructed so that each half thereof forms an arc of a circle from its respective 110

standard end toward the center of the rod. A shutter 35 is arranged in the cabinet A. The shutter is provided with a pedal lever 36. The turn table B is provided with a rubber mat 5 or cover 37 rigidly secured on its upper surface and upon the cover is a mat or facing 38 rigidly secured. The latter is preferably of celluloid. The rubber is to obviate vibrations in the disk and the celluloid is to 10 provide a hard, smooth and even surface upon which the disk shall travel. Means 39 are illustrated, by which the turn table B may be rotated for a length of time and speed as may be pre-determined. Any suitable 15 means, for example such as are employed in phonographs, may be used to rotate the turn table B. The axis 35' of each tone arm 10 and the arrangement of the disk thereon, are such that the arc of travel of 20 the engaging tread of the disks 29 upon the table B shall be from the center of the latter to its rim as illustrated. The fulcrum rod 34 is so arranged that when the record needle 24 is over its midpoint of travel between 25 the center and rim of the table B, as shown, the distance from the point of travel of the needle to the rod 34 is one-half the distance between the needle and the center of the diaphragm 19. Upon moving the 30 needle to its outermost point of travel toward the rim of the table B the distance between the point of travel of the needle and the rod 34 is two-thirds the distance between the needle and center of diaphragm. A related 35 ratio of such distances obtains at any point of travel where the needle may be.

The disks are arranged to engage the table B only sufficiently to cause them to rotate. The tone records are intended to carry the 40 same uniform, continuous tone of the human voice or of an instrument. The records may carry different tones of like character. Records may be substituted to produce any desired standard tone as desired.

45 It will be observed that the operation of the device consists in first starting the rotating means 39 which rotates the turn table B. This causes the disks 29 to rotate and the single, standard tone described is produced 50 from each record through the needle and diaphragm into a receiving tone arm 10 and thence transmitted to the mouth of the horn C whence it issues within the cabinet in a similar manner as with a phonograph. The 55 handles 11 are grasped by the operator and the disks are moved along their lateral path of travel. The fingers are placed upon the buttons to evenly depress or release the diaphragm holder 16. That is, when depressed, 60 the needle is raised and sound ceases. When released the spring 12 causes renewed engagement of the needle with the record. The fulcrum of the arm on the rod varies in relation to the position of the needle in 65 its lateral path of travel with respect to the

distance from said position to the fulcrum rod 34. The tone record is one of a fixed number of vibrations. When a disk is moved laterally it is obvious that a varying speed is produced in it by the turn table, 70 according to the position of the concentric circle upon the table to a point in which circle the disk is moved. Any variation in the speed of the disk will produce from its tone record, corresponding variations in the number of vibrations transferred from record to diaphragm, that is to say variations in tone pitch will be delivered through the horn outlet. Now, by moving the disks laterally from point to point a melody is produced 75 if the points are in proper relation to each other. If the same fulcrum of the needle bar on the fulcrum rod was preserved while the disks were laterally moved and throughout the variations of pitch, there would not 80 follow a corresponding inverse variation of amplitude to equalize the tone volume. To secure an unvarying volume throughout a varying pitch, the fulcrum rods are arranged at distances from the path of travel 85 as described. This arrangement will cause the needle bar to vary the amplitude of vibrations transmitted to the diaphragm in inverse ratio to their frequency. The principle thus embodied in the device is consonant 90 with the known laws of acoustics. It will be observed that if a disk is moved laterally from its illustrated mid position of travel to the rim of the table B the speed 95 of the disk and its record will be doubled, 100 but the amplitude of the vibrations received by the diaphragm will vary inversely, that is, they will be one-half. The ratio of amplitude of the vibrations in the diaphragm and the same vibrations in the needle point 105 in the mid position are as 1 to 1 but in the outer position referred to they are as 1 to 2. By proper calculation the ratio of vibrations occurring when the needle bar has any given fulcrum on the rod 34 may be 110 determined in a like manner. The shutter 35 is provided to regulate the volume of tone to be emitted from within the cabinet outwardly. The shutter is operated by pedal lever means as shown. It is to accomplish 115 the foregoing results that the fulcrum rod 34 is arranged in a pre-determined position with relation to the lateral path of travel of the needle. The springs 12 cause the needle point to engage the record groove with a 120 pre-determined pressure. It is apparent that the spring 12 draws the diaphragm holder 16 upward and this in turn draws the secured end of the bar 21 upward, which latter, having its fulcrum on the rod 34 125 causes a downward movement of the needle at the opposite end and into engagement with the record in its groove.

I contend that when my device is skillfully operated, tones, harmonies and melo- 130

dies can be produced from the standard, unit tones of the records, with greater ease than from the original instrument, for example, from whose tone the record was made. I contend that I have devised a method comparable to a violin string which is tuned to a single key tone, but without the difficulties met with in retaining the string at a given pitch. The device will 5 also enable an operator to produce glide tones from records of standard tones taken from instruments the nature of which prohibits the production of such tones from the originals.

15 I claim—

1. In a device of the character described, the combination of a horizontally arranged diaphragm, a needle bar rigidly secured at one end below the diaphragm in and to the center thereof, a vertical needle extending downwardly from the free end of said bar, a vertically rotatable circular tone record having a continuous groove in its circumferential edge in which a standard, unit tone is 20 registered for reproduction, means to secure said record below the needle in a position to allow the latter to continuously engage the former while rotating, and means to suspend the diaphragm in a position to retain the needle in uniform engagement with the record, substantially as described.

2. In a device of the character described, the combination of a horizontally arranged holder, a horizontal diaphragm rigidly secured therein, a needle bar having a longitudinal slot therein rigidly secured at one end below the diaphragm in and to the center thereof, said bar extending outwardly and being provided with a vertical needle 25 in its free end, a vertically rotatable circular tone record having a continuous groove in its circumferential edge in which a standard, unit, continuous tone is registered for reproduction, means to secure said record below said needle in a position where the latter can engage the record in its groove as the former is rotated, means to suspend the diaphragm holder in a position to retain the needle in uniform engagement with the record in a pre-determined manner, means 30 to move the needle and the record laterally in a circular path of travel, a fulcrum rod rigidly secured in the rear of the needle at a pre-determined distance in all its parts 35 from the lateral arc of travel of the needle said rod extending through the slot of said needle bar, substantially as described.

3. In a device of the character described, a rotatable horizontal turn table B having 40 a central supporting shaft, a horn secured in a rigid position, a lateral horizontal tube the center of which opens into said horn, horizontal tone arms pivoted at one end in the ends of said lateral tube said tone arms 45 extending over the table and terminating

in vertical ends, a horizontally arranged holder retained upon and in suspension from each vertical tone arm end, a horizontal diaphragm rigidly secured in the holder, a needle bar having a longitudinal slot therein 50 rigidly secured at one end below the diaphragm in and to the center thereof, said bar extending outwardly and being provided with a vertical needle in its free end, a vertically rotatable disk having means to retain it to the tone arm in a position wherein the disk may be engaged by the table, a vertical circular tone record having a continuous groove in its circumferential edge in which a standard, unit, continuous tone is registered for reproduction, means to secure said record upon one side of the disk below the needle in a position where the latter can engage the record groove as the former is rotated, means about the tone arm end to 55 suspend the diaphragm holder in a position to retain the needle in uniform engagement with the record in a pre-determined manner, a fulcrum rod rigidly secured in the rear of the needle at a predetermined distance in all 60 its parts from the lateral arc of travel of the needle said rod extending through the slot of the needle bar, substantially as described.

4. In a device of the character described, a rotatable horizontal turn table B having 65 a central supporting shaft, a rubber mat rigidly secured upon the upper surface of the turn table, a celluloid mat rigidly secured upon the upper surface of said rubber mat, a horn secured in a rigid position, a lateral 70 horizontal tube the center of which opens into said horn, horizontal tone arms pivoted at one end in the ends of said lateral tube said tone arms extending over the table and terminating in vertical ends, a horizontally arranged holder retained upon and in suspension from each vertical tone arm end, a horizontal diaphragm rigidly secured in the holder, a needle bar having a longitudinal slot therein 75 rigidly secured at one end below the diaphragm in and to the center thereof, said bar extending outwardly and being provided with a vertical needle in its free end, a vertically rotatable disk having means to retain it to the tone arm in a position wherein the disk may be engaged by the table, a vertical circular tone record having a continuous groove in its circumferential edge in which a standard, unit, continuous tone is registered for reproduction, means to secure said record upon one side of the disk below the needle in a position where the latter can engage the record groove as the former is rotated, means about the tone arm end to 80 suspend the diaphragm holder in a position to retain the needle in uniform engagement with the record in a pre-determined manner, a fulcrum rod rigidly secured in the rear of the needle at a predetermined distance in all 85 its parts from the lateral arc of travel of the needle said rod extending through the slot of the needle bar, substantially as described.

4. In a device of the character described, a rotatable horizontal turn table B having 90 a central supporting shaft, a rubber mat rigidly secured upon the upper surface of the turn table, a celluloid mat rigidly secured upon the upper surface of said rubber mat, a horn secured in a rigid position, a lateral 95 horizontal tube the center of which opens into said horn, horizontal tone arms pivoted at one end in the ends of said lateral tube said tone arms extending over the table and terminating in vertical ends, a horizontally arranged holder retained upon and in suspension from each vertical tone arm end, a horizontal diaphragm rigidly secured in the holder, a needle bar having a longitudinal slot therein 100 rigidly secured at one end below the diaphragm in and to the center thereof, said bar extending outwardly and being provided with a vertical needle in its free end, a vertically rotatable disk having means to retain it to the tone arm in a position wherein the disk may be engaged by the table, a vertical circular tone record having a continuous groove in its circumferential edge in which a standard, unit, continuous tone is registered for reproduction, means to secure said record upon one side of the disk below the needle in a position where the latter can engage the record groove as the former is rotated, means about the tone arm end to 105 suspend the diaphragm holder in a position to retain the needle in uniform engagement with the record in a pre-determined manner, a fulcrum rod rigidly secured in the rear of the needle at a predetermined distance in all 110 its parts from the lateral arc of travel of the needle said rod extending through the slot of the needle bar, substantially as described.

4. In a device of the character described, a rotatable horizontal turn table B having 115 a central supporting shaft, a rubber mat rigidly secured upon the upper surface of the turn table, a celluloid mat rigidly secured upon the upper surface of said rubber mat, a horn secured in a rigid position, a lateral horizontal tube the center of which opens into said horn, horizontal tone arms pivoted at one end in the ends of said lateral tube said tone arms 120 extending over the table and terminating in vertical ends, a horizontally arranged holder retained upon and in suspension from each vertical tone arm end, a horizontal diaphragm rigidly secured in the holder, a needle bar having a longitudinal slot therein rigidly secured at one end below the diaphragm in and to the center thereof, said bar extending outwardly and being provided with a vertical needle in its free end, a vertically rotatable disk having means to retain it to the tone arm in a position wherein the disk may be engaged by the table, a vertical circular tone record having a continuous groove in its circumferential edge in which a standard, unit, continuous tone is registered for reproduction, means to secure said record upon one side of the disk below the needle in a position where the latter can engage the record groove as the former is rotated, means about the tone arm end to 125 suspend the diaphragm holder in a position to retain the needle in uniform engagement with the record in a pre-determined manner, a fulcrum rod rigidly secured in the rear of the needle at a predetermined distance in all its parts from the 130

lateral arc of travel of the needle said rod extending through the slot of the needle bar, substantially as described.

5. In a device of the character described, a 5 rotatable horizontal turn table B having a central supporting shaft, a horn secured in a rigid position, a lateral horizontal tube the center of which opens into said horn, horizontal tone arms pivoted at one end in 10 the ends of said lateral tube said tone arms extending over the table and terminating in vertical ends, a horizontally arranged holder retained upon and in suspension from each vertical tone arm end, a horizontal dia- 15 phragm rigidly secured in the holder, a needle bar having a longitudinal slot therein rigidly secured at one end below the dia- phragm in and to the center thereof, said bar extending outwardly and being pro- 20 vided with a vertical needle in its free end, a vertically rotatable disk having means to retain it to the tone arm in a position wherein the disk may be engaged by the table, a vertical circular tone record having a con- 25 tinuous groove in its circumferential edge in which a standard, unit, continuous tone is registered for reproduction, means to secure said record upon one side of the disk below the needle in a position where the latter can 30 engage the record groove as the former is rotated, means about the tone arm end to suspend the diaphragm holder in a position to retain the needle in uniform engagement with the record in a pre-determined 35 manner, a fulcrum rod rigidly secured in the rear of the needle at a predetermined distance in all its parts from the lateral arc of travel of the needle said rod extending through the slot of the needle bar, means to 40 transmit rotating power to the shaft of the turn table B, substantially as described.

6. In a device of the character described, a rotatable horizontal turn table B having a central supporting shaft, a horn secured

in a rigid position, a lateral horizontal tube 45 the center of which opens into said horn, horizontal tone arms pivoted at one end in the ends of said lateral tube said tone arms extending over the table and terminating in vertical ends, a horizontally arranged holder 50 retained upon and in suspension from each vertical tone arm end, a horizontal dia- phragm rigidly secured in the holder, a needle bar having a longitudinal slot therein rigidly secured at one end below the dia- phragm in and to the center thereof, said bar 55 extending outwardly and being provided with a vertical needle in its free end, a vertically rotatable disk having means to retain it to the tone arm in a position wherein the disk may be engaged by the table, a vertical circular tone record having a continuous groove in its circumferential edge in which a standard, unit, continuous tone is registered for reproduction, means to secure 60 said record upon one side of the disk below the needle in a position where the latter can engage the record groove as the former is rotated, means about the tone arm end to 65 suspend the diaphragm holder in a position to retain the needle in uniform engagement with the record in a pre-determined manner, a fulcrum rod rigidly secured in the rear of the needle at a pre-determined distance in all its parts from the lateral arc of 70 travel of the needle said rod extending through the slot of the needle bar, means to transmit rotating power to the shaft of the turn table B, a cabinet in and upon which the foregoing mechanism is placed said cabinet having an inclosure into which the horn extends, a shutter in said cabinet, means to open and close said shutter, substantially as 75 described.

RALPH COLLING.
